METALWORKING MACHINE

Alfred E. Drissner, Cleveland, Ohio, assignor to
The National Acme Company, Cleveland, Ohio,
a corporation of Ohio

Application August 21, 1936, Serial No. 97,157

45 Claims.

(Cl. 29—37)

This invention relates to metal working machines and particularly to that type commonly designated as automatic multiple spindle screw machines, the invention being illustrated as a five spindle bar machine.

An object of the invention is the provision of a low open top easily accessible, simplified and low cost machine of this class particularly adapted for short work such as the manufacture of bearing cones and cups although useful for the manufacture of bevel gears and other work.

A further object of the invention is the provision of an improved machine in which the driving mechanism including the motor change gear box for changing the spindle speed and feed gears is located behind the spindle carrier housing and under the chucking and feeding mechanism instead of being located as heretofore in a casing or housing spaced some distance from the work spindle carrier housing or casing whereby the machine is more compact, very much simplified in its construction and a materially less number of parts is required and at the same time a low open top and very much shorter machine is provided readily accessible for tooling and other operations.

Some of the important advantages of this improved machine are the accessibility of the tools and the open space below the main tool slide whereby all of the chips can be removed from one end of the machine without interfering with its operation. Also, the forming slides provided for the spindles are controlled independently and easily accessible with the speed and feed controlling unit entirely independent from the main spindle carrier housing and cam drum housing.

A still further object of the invention is the provision of an improved electrical indexing mechanism effective to index the work spindle carrier although it can also be used to index the tool carrier or turret of a single spindle machine.

Notwithstanding the low type of machine shown, the spindle carrier is of large diameter and in a five spindle machine such as shown, it is 38" in diameter although the diameter will vary according to the size, capacity and number of spindles used on the machine since the machine is well adapted for four, five, six or more spindles.

Obviously, with this enormously large spindle carrier, it would be very complicated and practically impossible to control the spindle carrier for indexing and locking by means of a Geneva movement or a fan gear indexing movement as previously used on other types of machines.

When indexing with a Geneva movement, the indexing arm has to contact with roller guides on the spindle carrier or must be indexed by means of a gear such as shown in the prior patent to Simpson et al., No. 2,033,490, of March 10th,

1936, assigned to the National Acme Company, the assignee of the present improvement. Such an indexing mechanism, however, would enlarge the machine and exert considerable strain on the indexing mechanism. Therefore, as stated, one of the objects of the invention is the provision of a very simple type of indexing mechanism overcoming the difficulties specified and which will index this enormous weight in the shortest time with the least complicated mechanism and strain and while it is particularly adapted for use with a machine of the type specified, it can also be used on smaller types of machines having a varying number of spindles without any change in the mechanism, thereby doing away with the use of index arms, Geneva movements and gear movements heretofore used. Thus, this improved electrical driving means eliminates not only the Geneva type of indexing and the use of all intermediate gearing but also driving clutches and friction drives all having certain well known disadvantages and, by reason of the fact that the motor shaft worm is directly driven by the motor and directly engages the peripheral gear of the indexable carrier, it forms a direct and powerful drive having high efficiency and effectiveness for indexing the carrier at speed and reducing to a minimum lost motion, wear of numerous intermediate parts and friction of such parts all present in prior types of indexing.

A still further object of the invention is the provision of an electrical indexing mechanism controlled by the locking bolt of the spindle carrier and having certain improved features hereinafter referred to.

In the drawings accompanying and forming a part of this specification, Fig. 1 is a side view of this improved machine.

Fig. 2 is a right hand end view of Fig. 1.

Fig. 3 is a transverse vertical sectional view taken on the line 3—3 of Fig. 1.

Fig. 4 is a transverse vertical sectional view taken on the line 4—4 of Fig. 1 and illustrates the electrical indexing mechanism. This figure illustrates a modification of the indexing mechanism in that a single centrally located cam shaft is used.

Fig. 5 is an enlarged partly sectional view of the electrical indexing mechanism.

Fig. 6 is a detail view of the locking bolt mechanism.

Fig. 7 is a side view looking toward the right in Fig. 6.

Fig. 8 is a partly sectional view of the duplicate cam shaft mechanism.

Fig. 9 is a partly sectional view illustrating the hand crank controlled portion of the machine and the switch mechanism controlled thereby when a single cam shaft such as illustrated in Fig. 4 is used.

Fig. 10 is a view of Fig. 9 looking toward the right.

Fig. 11 is an expanded plan view partly in section of the gear box mechanism operated from the main driving motor and within this gear box is housed the spindle change gears and the feed change gears; and

Fig. 12 is a transverse vertical section on the line 12—12 of Fig. 8.

10 Similar characters of reference indicate corresponding parts in the several views.

Before explaining in detail the present improvement and mode of operation thereof, I desire to have it understood that the invention is not limited to the details of construction and arrangement of parts illustrated in the accompanying drawings since the invention is capable of other embodiments, and that the phraseology employed is for the purpose of description and 20 not of limitation.

Framework

The framework of the machine comprises a pan-formed bed 2 having one upright 3 midway 25 of its length to house the spindle carrier and to the top of this upright is secured a top bracket 4 extending rearwardly and connected to the reel disk support 5 for the bar stock.

Spaced from this centrally located upright 3 is 30 another upright 6 of materially less height and forming a cam drum housing. It was in this cam drum housing when constructed materially larger in all dimensions and spaced farther away from the spindle carrier housing that the driving 35 mechanism including the gear box was heretofore located but which, however, in the present improved machine, is located behind the spindle carrier housing underneath the chucking and feeding mechanism and so eliminating all of this 40 mechanism from the cam drum housing.

Thus, this machine is made much shorter and much lower and materially simplified while giving free access to the chips and permitting them to drop freely into the open front space of the pan 45 between the two housings so that they can be removed from the pan without interfering with the operation of the machine through the half-moon shaped opening 7 in the cam drum housing.

To facilitate the removal of the chips from 50 this pan, a chip chute may be provided which can be turned to line up with the angle in the pan and this chute may be utilized as a guard over the half-moon shaped opening in the cam drum housing.

55 In this machine, substantially all of the movable parts are mounted within the housings with the exception of the main tool slide 11. The single driving shaft 20 and the two cam shafts 35 and 36 hereinafter referred to and located on opposite sides of the machine are also housed between the spindle carrier housing 3 and the cam drum housing 6 by side brackets 39 and 40 and these brackets connect the two housings 3 and 6 and are bolted to the chip pan so that both units 65 are of rigid construction.

Spindle carrier

The rotary spindle carrier 8 is mounted or 70 housed in the central upright 3 and comprises a pair of disks centrally and integrally connected and this spindle carrier carries the rotary work spindles 9 and their bearings of suitable type.

75 The rotary spindle bearing construction is of the usual type as is also the spindle chucking

mechanism, collets and feed tubes and are well known in multiple spindle machines.

5 Into this spindle carrier 8 a spindle carrier extenson, stem or shaft 10 is pressed, it extending the full length of the spindle carrier and is fastened thereto by dowel pins. This extension or shaft extends from the spindle carrier toward and into the cam drum housing or upright 6, being supported therein in a suitable manner. Thus, the rotary spindle carrier has a three- 10 point bearing, namely, the two disks and the opposite end of the stem or shaft in the drum housing.

15 This rotary spindle carrier is controlled endwise by a suitable thrust washer in front of the cam drum housing and a nut on the inside of this cam drum housing thus holding the spindle carrier and its stem or shaft rigidly both radially and otherwise.

Main tool slide

20 Mounted on the stem or shaft 10 is the main tool slide 11, it being guided by an upwardly projecting arm 12 sliding on a short guide bracket 13 secured to and projecting beyond the inner face of the cam drum housing and this assists in maintaining the tool slide in line with the work spindles. It will thus be observed that the spindle carrier housing or upright 3 and drum housing 6 are unconnected by a bar or beam heretofore considered necessary, thus leaving the machine entirely open at its top and so affording greater accessibility thereto.

25 This tool slide is shifted back and forth by a rod 14 secured to the tool slide and having a side arm 15 (see Figs. 2 and 3) carrying a cam roll in contact with a tool slide cam drum 16 suitably supported and geared to the cam shaft 35 hereinafter referred to, this cam drum being located in the cam drum housing 6.

30 The shaft 14 and therefore the main tool slide is also guided by a depending arm 14' having a forked end sliding on a short shaft 14'', all located within the cam drum housing.

Accelerated tool spindles

35 In this cam drum housing there is also located a cam drum 17 carrying a plurality of cams for controlling two additional tool spindles 17a and 17b designed for the purpose of accelerated 50 boring, turning, reaming, etc., and which work independently of the main tool slide 11 but are supported by a tool holder mounted on the tool slide.

40 This construction is such that if the main tool slide should travel, say, one inch to split up the drilling, rough boring or turning, the accelerated tool spindles controlled by this cam drum 17 can travel two or three times this distance to finish the piece. The cam drum 17 has its shaft suitably gear connected with the cam shaft 36 by a train of gears 17c and is driven thereby.

Driving mechanism

45 This improved machine is driven by a suitable motor 18 coupled with a gear box driving mechanism 19 (see Fig. 11) and this gear box houses the spindle change gears and feed change gears and is located below and at the rear end of the 55 rotary work spindles to eliminate overhang or 70 extremely high construction of the machine.

55 From this gear box the driving shaft 20 runs the full length of the machine and into the cam drum housing 6 and has within the cam drum housing, a driving chain 21. This chain drive 75

has a variable speed controlled by the gear box varying from 288 to 1500 R. P. M. and is controlled by the spindle change gears. The chain drives an intermediate gear 22 meshing with a gear 23 located on one end of the spindle driving shaft 24 extending through the spindle carrier stem or shaft and centrally through the rotary spindle carrier. At its opposite end it carries a gear 25 meshing with gears 26 carried by the rotary work spindles 9 which may vary in number from four to six or more depending upon the class of work to be operated upon.

Stock stop

15 The machine is provided with a suitable stock stop shown as an oscillating stop 28 (see Figs. 1 and 2) having an arm 28' operated from a suitable cam on the cam shaft 35.

Feeding mechanism

20 The feeding mechanism, by which is meant the mechanism that controls the main tool slide cam drum 16, the accelerated tools cam drum 17, the forming tools slide cam disks hereinafter referred to, the chuck opening cam drum and stock feed cam drum, controlling the movements of the forming tool slides, main tool slide 11, stock stop 28, etc., in other words, all of the cams which have to work simultaneously, is controlled from a gear box through a transverse or cross worm shaft 27 (see Fig. 8). This worm shaft 27 carries a pair of worms 31 and 32 respectively meshing with worm wheel gears 33 and 34 mounted on cam shafts 35 and 36 carrying the cam drums 37 and 38 and their cams. This worm shaft 27 thus controls the movement of these two cam shafts and the cam drums mounted thereon which are located under the spindle carrier. These cam shafts extend into the cam drum housing 6 on both sides thereof and the construction allows the spindle carrier to be located as low as possible. The worm shaft is rotated by a worm gear mechanism 39 driven by a splined shaft which is a continuation of the feed drive shaft 71 (see Fig. 11).

45 This worm shaft has a clutch 72 operated by a crank handle as is usual on automatic machines of this type to enable the operator to control by hand all the tool slides through the medium of the cam shaft and worm for setting his tools.

Side and top slides

50 At each side of the machine there are two superposed side or cross forming slides 41 and 42 and each pair is operated from cam disks 43 and 44 carried on the cam shafts 35 and 36 by means of a system of rack-segment formed levers 45 and 46. The side forming slides are of vertical shape to eliminate overhang and are 60 easily accessible for the tools.

The top slide 47 which is an additional or auxiliary slide and can be used for forming, cutting off, shaving, knurling, etc., is operated by a cam disk 48 by means of a chain drive 49 from the cam shaft 36.

65 From the foregoing it will be seen that the gear box mechanism, instead of being located as heretofore in the cam drum housing is located in the rear of the spindle carrier below the plane 70 of the rotary spindles and at this end of the machine, thus enabling the machine to be very much shortened and lowered, in other words, more compact notwithstanding the very large size of the spindle carrier which, in the machine 75 shown, carries rotary spindles capable of han-

dling 5" bar stock and which, in the ordinary type of machine, would mean a machine of enormous size.

Electrical indexing mechanism for the spindle carrier

As before stated, it would be very complicated and almost impossible to index and lock such an enormous spindle carrier by a Geneva movement or a fan gear index movement such as commonly used. When indexing with the Geneva movement, the indexing arm has to contact roller guides on the spindle carrier or must be indexed by means of a gear, all of which would 10 enlarge the machine and put a considerable 15 strain on the indexing mechanism.

In the present improvement, this is all eliminated by a very small type of indexing mechanism which is effective to directly index the enormous weight of the spindle carrier in the 20 shortest time with the least strain and least complicated mechanism, this being accomplished by means of an electrical indexing mechanism comprising generally a worm gear carried by the spindle carrier, a worm in mesh therewith and 25 carried by a worm shaft mounted in suitable bearings, a spring on the shaft and an electric motor, the worm shaft being shown as a part of the motor shaft and this electrical mechanism is controlled by a switch which in turn is 30 controlled by the lock bolt for locking the spindle carrier after each indexing thereof.

Spindle carrier locking mechanism

The spring pressed lock bolt 50 (see Figs. 6 and 35 7) is suitably mounted to engage recesses or seats 51 in the side of the rotary spindle carrier 8 and is controlled from the cam shaft 36 by means of a cam 52 (see Figs. 4 and 7) shaped to disengage the lock bolt from its seat. At this time, however, the spindle carrier is still held in position by means of the worm gear indexing means. As soon as the lock bolt leaves its bolt seat with very little clearance, it contacts a switch 53 by means of a lever 54 which, in turn, starts the indexing 40 motor 55 (see Figs. 4 and 5). This motor rotates the indexing worm shaft 55' in mesh with the worm gear 56 carried by the rotary spindle carrier 8, thus starting the rotary or indexing movement of the rotary spindle carrier 8. As 45 soon as this spindle carrier starts its rotating movement, the lock bolt lifting cam 52 on the cam shaft 36 allows the spring pressed lock bolt to contact with the outside periphery of the spindle carrier and so maintains electrical contact until the next lock bolt seat comes in line with the lock bolt whereupon the lock bolt enters the tapered portion of the lock bolt seat.

55 As soon as the lock bolt partly enters its seat, it disengages the switch 53 which shuts off the current to the motor and by means of the motor governor or motor control 57, the motor 55 is stopped within one-half a turn so that the lock bolt can enter its bolt seat at the proper place without danger of overrunning, thus allowing the lock 60 bolt to be seated securely in its seat through the medium of its spring 58 which is a very heavy spring.

65 On the worm shaft is also a very heavy spring 59 to cushion the worm so that there is no strain 70 on the worm gear if the spindle carrier should have to move slightly backward or forward to allow the lock bolt to properly seat.

The worm shaft of this indexing mechanism, as before stated, is shown integral with the motor 75

shaft and extends through the spindle carrier housing for the reception of a crank handle 60 (see Fig. 5) which may be used in the event the operator desires to turn the spindle carrier by hand.

To prevent the spindle carrier from being turned while the current is on, a switch 61 which controls the electrical current is provided and this switch is controlled by a cover plate 62.

10 When this cover is on, the spring plunger 63 of the switch closes the contact points of the switch and permits the proper operation of the indexing mechanism. When the cover plate 62 is removed to permit the crank handle 60 to be applied and used, the spring plunger 63 opens the contact points and breaks the electrical circuit, thus preventing electrical operation of the indexing mechanism.

To insure that this motor controlled electrical indexing mechanism and bolt controlled switch 20 53 will be properly timed and not get out of such timing, which might happen in the event the spindle carrier just starts to rotate and the operator should throw out the feed clutch controlling the cam shaft 36 and thus turn the lifting cam for the lock bolt and as there is also the possibility that the lifting cam for the lock bolt may stop at the high point when the clutch controlling the shaft 36 is disengaged, a safety mechanism is provided (see Figs. 9 and 10). The rod connected handle levers 64 on both sides of the machine control the entire feeding movements of the cam shaft when the clutch 65 controlling this feed cam shaft is disengaged by the handle levers 35 64 and at this time the entire movement of the cam shaft is stopped. At this time, also, a switch 66 controlled by a collar 67 connected with one of the handle levers 64 operates to cut off the current from the indexing mechanism.

40 Thus, by operating either of the handle levers 64, the entire indexing and feeding mechanism is instantly stopped, one of these handle levers being located, as before stated, at each side of the machine. This switch 66, of course, only controls 45 the current for the indexing mechanism and does not control the main driving motor 18 from which the rotary spindles are driven.

The connected hand levers 68 at opposite sides of the machine are only used for hand control 50 of the high and low speed movement of the cam shaft which controls the cutting time and idle time of the machine.

The machine is provided with suitable clutch and brake mechanism 69 and 70 shown located 55 on the feed drive shaft 71 (see Fig. 11).

There are, of course, other associated and co-operating features in a machine of this kind not deemed necessary to describe herein in detail except to say the shaft designated the feed drive 60 shaft 71 (Fig. 11) includes a clutch shaft coupled thereto by the coupling H and carries clutches 69 and 70. The clutch 70 is driven by a gear L as the shaft carrying the gear M is, in the assembled machine, located over the shaft 71, therefore 65 by shortening the gear box and having all of the gears and driving mechanism in a short compact unit.

The gear M is driven directly from the motor by means of a chain sprocket mechanism N. 70 When clutch 70 is engaged, the transverse worm shaft 27 (Fig. 8) will be rotated at high speed for returning the tool slide and controlling the indexing mechanism for the spindle carrier, at the same time advancing the stock feed tube to bring 75 the material to the stock stop.

When the clutch sleeve O controlling clutches 69 and 70 is shifted by means of suitable cams in the machine toward the clutch brake 69, this brake slows down the worm shaft speed from high to low until the roller clutch P engages 5 clutch shaft 71 for a positive slow feed drive. In other words, the clutch 70 is a high speed clutch and clutch 69 is a combination of brake and clutch for quick high and slow operating means connected directly to the slow speed gear by means 10 of the roller clutch P.

The drive shaft Q through the coupling R drives a shaft 20 controlling the work spindle speeds by means of a chain 21, gears 22 and 23 through the center drive shaft 24 (see Figs. 3 15 and 1) which shaft 24, as before stated, goes through the spindle carrier stem. This shaft Q is provided with change gears Y to change the spindle speeds of the work spindles. The shaft Z controls the feed mechanism through change 20 gears A.

The driving shaft 20 is driven from the shaft O, Fig. 11, through the coupling R and is controlled through the change gears A and Y. A indicates the change gears for the feeding mechanism to 25 drive the feed drive shaft 71 and Y indicates the change gears for the spindle drive shaft 20. Thus, the shaft 20 is connected through R with Q as one unit to the gear box of Fig. 11.

The shaft 71 of Fig. 11 has two clutches for 30 high and low speed which control the worm shaft 39 engaging the worm and clutch 72 and shaft 27 (see Fig. 8). The shaft 27 controls the two cam shafts 35 and 36. This shaft 27 can be engaged and disengaged through the clutch 72 and 35 this clutch controls the stopping and starting of the entire feeding mechanism. Both shafts 35 and 36 are always connected together so that the cams located on both shafts are timed correctly.

Thus, the entire construction to control the 40 stopping and starting of the feeding mechanism is controlled by the clutch 72 and the high and low speed shaft 39 which is coupled with the shaft 71 is controlled for high and low speeds by the clutches 69 and 70.

Q, R and 20 is one unit to drive the work 45 spindles and is independent of the shaft 71 which, with H and 39, form a second unit to control the feeding mechanism.

By indexing the spindle carrier electrically, this 50 makes it possible to build a large type multiple spindle machine very low to the ground all operating parts of which, including those at the top of the machine are easily accessible to and within the reach of the operator.

From the foregoing, it will be seen that when 55 the indexing mechanism is stopped, this does not stop the main motor controlling the rotation of the spindles in the work spindle carrier. These continue to rotate.

All of the units of this machine with the exception of the motors are flooded in oil by means of a splash oil system and the cutting oil or lubricant for cooling the tools is controlled by a cutting oil pump conveniently located in the pan, and underneath the work chucking and feeding mechanism is provided a space for water cooling the oil. The cam operated drums enclosed in the cam drum housing are also lubricated by means 60 of an oil splash system.

In conclusion, it will be observed that the machine, although capable of handling very large bar stock and, therefore, having a massive and consequently heavy rotary spindle carrier, this carrier is very easily indexed in an expeditious 70 75

and rapid manner without the use of the complicated mechanism heretofore used in multiple spindle machines and that, furthermore, by the location of a large part of the mechanism heretofore mounted within the cam drum housing at the opposite end of the machine in the rear of the spindle carrier and under the chucking and feeding mechanism for the spindles, a very low machine and a very short machine is provided, the lessened height of the machine enabling the operator easily to reach all of the tools, thus facilitating the tooling of the machine while the accessibility at all times is increased, especially as the machine is open at the top, having no connecting bar or beam between the two housings, one of which, as before stated, is located centrally of the length of the bed instead of, as heretofore, one at each end of the bed of the machine, thus enabling the stock reel carrying the stock bars to be efficiently supported by a beam connecting the stock reel support and the tool carrier housing and so materially shortening the space necessary for the mounting of the machine in the shop.

25 It is to be understood that, by describing in detail herein any particular form, structure or arrangement, it is not intended to limit the invention beyond the terms of the several claims or the requirements of the prior art.

30 Having thus explained the nature of my said invention and described a way of constructing and using the same, although without attempting to set forth all of the forms in which it may be made or all of the modes of its use, I claim:

35 1. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, chucking and feeding mechanisms for the rotary work spindles, and actuating means including a change speed gear box located behind the spindle carrier housing and underneath the chucking and feeding mechanisms.

40 2. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, chucking and feeding mechanisms for the rotary work spindles, actuating means including a change speed gear box located behind the spindle carrier housing and underneath the chucking and feeding mechanisms, and projecting means carried by one housing and spaced from the other for guiding the sliding tool carrier.

45 3. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, chucking and feeding mechanisms for the rotary work spindles, actuating means including a change speed gear box located behind the spindle carrier housing and underneath the chucking and feeding mechanisms, and projecting means carried by one housing and spaced from the other for guiding the sliding tool car-

50 rier and comprising a bracket carried on the top of said housing.

4. In a machine of the class described, the combination of a bed, a pair of spaced housings, one located substantially midway of the bed, an indexable work holder or spindle carrier mounted in the latter housing, an axially supported tool slide, means for reciprocating said slide, means for guiding said slide, and a change speed power unit located below the plane of the spindles and in the rear of the spindle carrier.

5. In a machine of the class described, the combination of a spindle or work holding carrier, a tool carrier, electrically operated means for indexing one of said carriers, means for locking the indexable carrier, and means controlled by the locking means for starting and stopping the electrical means for operating the indexing means.

6. In a machine of the class described, the combination of a spindle or work holding carrier, a tool carrier, and electrically operated means for indexing one of said carriers and comprising a motor, a worm shaft directly driven by said motors, a gear carried by said indexable carrier and in mesh with said worm shaft, means for locking the indexable carrier and comprising a bolt, and means controlled by the locking bolt for starting and stopping the motor and thereby the electrically operated indexing means.

7. In a machine of the class described, the combination of a spindle or work holding carrier, a tool carrier, electrically operated means for indexing one of said carriers, means for locking the indexable carrier, means controlled by the locking means for starting and stopping the electrical means for operating the indexing means, and means for shifting the locking means into engagement with the periphery of the indexable carrier in readiness to lock the carrier.

8. In a machine of the class described, the combination of a spindle or work holding carrier, a tool carrier, and electrically operated means for indexing one of said carriers and comprising a motor, a worm shaft directly driven by said motor, a gear carried by said indexable carrier and in mesh with said worm shaft, means for locking the indexable carrier and comprising a bolt, means controlled by the locking bolt for starting and stopping the motor and thereby the electrically operated indexing means, and means for shifting the locking bolt into engagement with the periphery of the indexable carrier in readiness to lock the carrier.

9. In a machine of the class described, the combination of a spindle or work holding carrier, a tool carrier, electrically operated means for indexing one of said carriers, means for manually cranking the machine, and means for cutting off the electric power from the motor to the indexing means during the manual cranking thereof.

10. In a machine of the class described, the combination of an upright housing, an indexable work holder or spindle carrier therein, a stock reel carrier, a top bracket connecting the reel carrier and spindle carrier housing, a cam drum housing, a sliding axially supported tool carrier between said housings, and a cam drum within the drum housing for reciprocating the tool carrier.

11. In a machine of the class described, the combination of a pair of upright housings spaced apart forming an open top type machine, an indexable work holder or spindle carrier within one of said housings, a sliding axially supported tool carrier between said housings, accessory tool

75

- spindles between said housings, and a change speed power unit located below the plane of the spindles and in the rear of the spindle carrier.
12. In a machine of the class described, the combination of a pair of upright housings spaced apart forming an open top type machine, and indexable work holder or spindle carrier within one of said housings, a sliding axially supported tool carrier between said housings, accessory tool spindles between said housings, a cam drum within said drum housing for operating them, a stock reel carrier, and a bracket connecting the tops of said stock reel carrier and the indexable carrier housing.
13. In a machine of the class described, the combination of a pair of upright housings spaced apart forming an open top type machine, an indexable work holder or spindle carrier within one of said housings, a sliding axially supported tool carrier between said housings, accessory tool spindles between said housings, a cam drum within said drum housing for operating them, a stock reel carrier, a bracket connecting the tops of said stock reel carrier and the indexable carrier housing, and a bracket secured to the top of the drum housing and spaced from the spindle carrier housing for guiding the sliding tool carrier.
14. In a machine of the class described, the combination of a pair of upright housings spaced apart and forming an open top type machine, an indexable rotatable spindle carrier within one of said housings, an actuating cam drum within the other housing, and a chip receiving pan under the space between said housings and accessible at the end thereof under the drum housing.
15. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, chucking and feeding mechanisms for the rotary work spindles, actuating means including a change speed gear box located behind the spindle carrier housing and underneath the chucking and feeding mechanisms, and transversely operated slides on one or both sides of the machine, and actuating means therefor located below the spindle carrier.
16. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, chucking and feeding mechanism for the rotary work spindles, a pair of cam shafts located one at each side of the machine, and a transversely extending worm shaft for operating said cam shafts and located below the spindle carrier.
17. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, chucking and feeding mechanism for the rotary work spindles, a pair of cam shafts located one at each side of the machine, a transversely extending worm shaft for operating said cam shafts and located below the spindle carrier, and change speed gearing also located behind and below the spindle carrier for controlling said worm shaft.
18. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, a cam shaft located below the work spindle carrier, and a power unit for operating said cam shaft and rotating the spindles and located behind said indexable work spindle carrier.
19. In a machine of the class described, the combination of a pair of upright housings spaced apart and forming an open top type machine, an electrically indexed work holder or spindle carrier mounted in one of said housings, rotary work spindles carried by said carrier, an axially supported reciprocating tool slide located between said housings, cam shafts located below the work spindle carrier, and a power unit for operating said cam shafts and rotating the spindles and located behind said indexable work spindle carrier and effective to control the speed of the rotary work spindles and the speed of the cam shafts.
20. In a machine of the class described, the combination of a pair of upright housings spaced apart and forming an open top type machine, an indexable work holder or spindle carrier mounted in one of said housings, rotary work spindles carried by said carrier, an axially supported reciprocating tool slide located between said housings, a pair of cam shafts located below the work spindle carrier one at each side of the machine, and a power unit for actuating the rotary spindles and cam shafts and effective to control the speed of rotation of the rotary spindles and said cam shafts and located below the work spindle carrier.
21. In a metal working machine having an indexable carrier or turret, electrically operated means for indexing said turret, means for locking the indexable turret, and means controlled by the locking means for starting and stopping the electrical means for operating the indexing means.
22. In a metal working machine having an indexable carrier or turret, electrically operated means for indexing said turret and including a switch, and means for controlling the operation of the switch and comprising means for locking the indexable turret, the contact of said switch effective fully to index said carrier.
23. In a metal working machine having an indexable carrier or turret, electrically operated means for indexing said turret, means for manually indexing the turret, and means for disconnecting the electrical current when the indexing mechanism is manually operated.
24. In a metal working machine having an indexable carrier or turret, electrically operated means for indexing said turret, a cam shaft, means for stopping the cam shaft, and means thrown into operation on the stoppage of the cam shaft to stop the indexing mechanism.
25. In a machine of the class described, the combination of an indexable spindle or work holding carrier, a sliding tool carrier, means for reciprocating said tool carrier, electrically operated means for indexing said spindle carrier, means for locking the indexable carrier, and means controlled by the locking means for starting and stopping the electrical means for operating the indexing means.
26. In a machine of the class described, the

combination of an indexable spindle carrier, a plurality of rotary work spindles carried thereby, a reciprocating tool carrier, and electrically operated means for intermittently indexing said spindle carrier and including a switch, and automatically operative means for controlling the operation of said switch.

27. In a machine of the class described, the combination of an indexable spindle carrier, a plurality of rotary work spindles carried thereby, a reciprocating tool carrier, and electrically operated means for intermittently indexing said spindle carrier and including a switch, automatically operative means for controlling the operation of said switch, and means for manually cranking the machine.

28. In a metal working machine having an indexable carrier or turret provided with a peripheral gear, a shaft extending transversely to the axis of said carrier and having a worm in engagement with said peripheral gear, and an electrically operated motor at the end of and in direct engagement with said shaft for indexing said carrier and carrier locking means for controlling the operation of said motor.

29. In a machine of the class described, the combination of an indexable spindle carrier having a peripheral gear, a plurality of rotatable spindles carried by the carrier, a sliding tool carrier, electrical driving means for the spindles and tool carrier, and electrically operated means for indexing said spindle carrier and comprising a worm shaft in mesh with the peripheral gear of the carrier, and a motor at one end of said shaft and in direct engagement therewith.

30. In a machine of the class described, the combination of an indexable spindle carrier having a peripheral gear, a plurality of rotatable spindles carried by the carrier, a sliding tool carrier, electrical driving means for the spindles and tool carrier, and electrically operated means for indexing said spindle carrier and comprising a worm shaft in mesh with the peripheral gear of the carrier, a motor at one end of said shaft and in direct engagement therewith, means for locking the indexable carrier, and means controlled by said locking means for starting and stopping the electrically operated indexing means.

31. In a metal working machine having an indexable spindle carrier with its axis located in a horizontal plane and provided with a peripheral gear, a plurality of rotary spindles carried by the carrier, a sliding tool carrier, electrically operated driving means for the spindle and tool carrier thereby to reciprocate the tool carrier, and electrically operated means for indexing the spindle carrier and including a worm shaft located transversely of the spindle carrier and below the same and in mesh with the peripheral gear of said carrier.

32. In a metal working machine having an indexable carrier or turret and electrically operated means for indexing the carrier and including a shaft located externally of and at the outer periphery of said carrier and extending transversely to the carrier, intermeshing gearing carried by said carrier and shaft, means for locking said indexable carrier, and means controlled by the locking means for starting and stopping the electrical means for operating the indexing means.

33. In a metal working machine having an indexable carrier or turret provided with a plurality of rotatable spindles, electrical driving means for rotating the spindles, and electrically

operated means for indexing said carrier and including a shaft located externally of and at the outer periphery of said carrier and extending transversely to the carrier, intermeshing gearing carried by said carrier and shaft, means for locking said indexable carrier, and means controlled by the locking means for starting and stopping the electrically operated indexing means without stopping the electrical driving means.

34. In a metal working machine having an indexable carrier or turret and a cam shaft for controlling operating elements of the machine, electrical driving means for said cam shaft, electrically operated means for directly indexing said carrier, and means controlling the starting and stopping of the electrically operated indexing means independently of the electrical driving means for the cam shaft.

35. In a metal working machine comprising a work carrier and a tool carrier, one indexable relative to the other, one having a rotatable spindle, electrical driving means for rotating said spindle, electrically operated means for directly indexing one of said carriers, and means intermittently operating the electrical means and thereby said indexing means independently of the operation of said electrical driving means.

36. In a metal working machine comprising a work carrier and a tool carrier, one indexable relative to the other and one reciprocal relative to the other and one having a rotatable spindle, electrical driving means for rotating said spindle and reciprocating one carrier, electrically operated means for directly indexing one of said carriers, and means intermittently operating the electrical means and thereby said indexing means independently of the operation of said electrical driving means.

37. In a machine of the class described, the combination of a bed, a pair of upright housings carried by said bed and spaced apart and forming an open top type machine, an indexable work holder or spindle carrier mounted in one of said housings, rotary work spindles carried by said carrier, a reciprocating tool slide located between said housings, and a change speed power unit supported below the plane of said work spindles and in the rear of said spindle carrier.

38. In a machine of the class described, the combination of a bed, a pair of spaced housings, one located substantially midway of the bed and forming an open top type machine, an indexable work holder or spindle carrier mounted in the latter housing, rotary work spindles carried by said carrier, a reciprocating tool slide between the housings, and a change speed power unit located below the plane of the work spindles and in the rear of said spindle carrier.

39. In a machine of the class described, the combination of a spindle or work holding carrier, a tool carrier, and electrically operated means for indexing one of said carriers, means for locking said carrier, and a switch operated thereby, the contact of said switch effective fully to index said carrier.

40. In a machine of the class described, the combination of a pair of upright housings spaced apart and forming an open top type machine, an electrically indexed work holder or spindle carrier mounted in one of said housings, rotary work spindles carried by said carrier, a reciprocating tool slide located between said housings, a cam shaft located below the work spindle carrier, and a power unit for operating said cam shaft and rotating the spindles and located be-

hind said indexable work spindle carrier and effective to control the speed of the rotary work spindles and the speed of the cam shaft.

41. In a machine of the class described, the combination of a pair of upright housings spaced apart and forming an open top type machine, a directly driven electrically indexed work holder or spindle carrier mounted in one of said housings, rotary work spindles carried by said carrier, a reciprocating tool slide located between said housings, a cam shaft located below the work spindle carrier, and a power unit for operating said cam shaft and rotating the spindles and located behind said indexable work spindle carrier and effective to control the speed of the rotary work spindles and the speed of the cam shaft.

42. In a metal working machine having an indexable carrier or turret, electrically operated means for intermittently indexing said carrier, means for locking the carrier after each indexing, a cam shaft for controlling the operation of said locking means, and automatically operative electrical means thrown into operation on the unlocking of the carrier by the cam shaft to throw into operation the electrical indexing means and on the locking of the carrier to throw out of operation the electrical indexing means.

43. In a metal working machine having an indexable carrier or turret, electrically operated means for intermittently indexing said carrier, means for locking the carrier after each indexing, a cam shaft for controlling the operation of said locking means, and automatically operative electrical means thrown into operation by

the locking means on the unlocking of the carrier by the cam shaft to throw into operation the electrical indexing means and on the locking of the carrier to throw out of operation the electrical indexing means.

44. In a metal working machine having an indexable carrier or turret having a peripheral gear, electrically operated means for intermittently indexing said carrier and comprising a motor and a gear shaft driven by the motor and in mesh with said carrier gear, means for locking the carrier after each indexing, a cam shaft for controlling the operation of said locking means, and automatically operated electrical means thrown into operation on the unlocking of the carrier by the cam shaft to throw into operation the electrical indexing means and on the locking of the carrier to throw out of operation the electrical indexing means.

45. In a metal working machine having an indexable carrier or turret having a worm gear, electrically operated means for intermittently indexing said carrier and comprising a motor and a worm shaft driven by the motor and in mesh with said carrier worm gear, means for locking the carrier after each indexing, a cam shaft for controlling the operation of said locking means, and automatically operated electrical means thrown into operation by the locking means on the unlocking of the carrier by the cam shaft to throw into operation the electrical indexing means and on the locking of the carrier to throw out of operation the electrical indexing means.

ALFRED E. DRISSNER. 35
